(57) **CLAIM**

The ornamental design for a combination “wet/dry vacuum cleaner,” as shown and described.

DESCRIPTION

FIG. 1 is a front and right side perspective view of a combination wet/dry vacuum cleaner showing my new design;

FIG. 2 is a front elevational view thereof;

FIG. 3 is a left side elevational view, the right side elevational view being a mirror image thereof;

FIG. 4 is a top plan view thereof; and,

FIG. 5 is a rear elevational view thereof.
